T. J. BARGER

OIL WELL PUMP

Filed Dec. 5, 1922

FIG. 1.

FIG. 3.

FIG. 2.

Inventor
Tom J. Barger.
by Herbert H. Jenner,
Attorney.

UNITED STATES PATENT OFFICE.

TOM J. BARGER, OF OILTON, OKLAHOMA.

OIL-WELL PUMP.

Application filed December 5, 1922. Serial No. 605,055.

To all whom it may concern:

Be it known that I, TOM J. BARGER, a citizen of the United States, residing at Oilton, in the county of Creek and State of Oklahoma, have invented certain new and useful Improvements in Oil-Well Pumps, of which the following is a specification.

This invention relates to pumps provided with sand traps and chiefly used in connection with oil wells; and it consists in the novel construction and combination of the parts hereinafter fully described and claimed whereby the sand is guided into the sand trap and prevented from passing backwardly into the pump barrel.

In the drawings, Figure 1 is a vertical section through a pump provided with a sand trap and a sand guide according to this invention. Fig. 2 is a sectional plan view, taken on the line 2—2 in Fig. 1. Fig. 3 is a vertical section through the guide 13 and stem 13' showing a preferred modification in the form of the passage 21.

The pump barrel 4 is secured at its lower end to a coupling sleeve 5, and the lower end of the sand trap 6 is also secured to this sleeve so that it encircles the pump barrel. The sand trap is a long cylindrical vessel, and the sleeve 5 forms the bottom of it. The suction pipe 7 is also secured to the sleeve 5, and is provided with a foot valve in the usual manner. The plunger 8 works in the pump barrel 4, and is of any approved construction. The delivery valve 9 is inserted in a cage 10 which is secured to the upper end of the plunger. The pump rod 12 is secured to the upper end of the cage 10.

The upper end portion of the pump barrel 4 is retained centrally and steadied within the sand trap by distance pieces 14 which do not materially obstruct the sand trap, and the upper end of the sand trap is connected to the delivery pipe 15 of the pump by a conical coupling sleeve 16. The pump rod 12 slides in a guide 13 supported at the top of the pump barrel.

The guide has outlet passages 19 which deliver upwardly, and it is preferably a little larger in diameter than the pump barrel so that it rests on the upper end of it. Suitable packing devices 20 are secured to the guide 13, and are slideable within the pump barrel so that they may be removed and replaced. These packing devices and the pump plunger are preferably provided with suc-

tion cups such as used on pump plungers of approved construction. The packing devices have a longitudinal outlet 21, and a cage 22 is secured to their lower end. In the preferred form of the device shown in Fig. 3, a single passage 21 for the oil is provided in the stem 13' of the guide 13, which passage communicates with the passages 19 of the guide. The packing devices are secured on the stem 13' by the cage 22 which is screwed on the lower end portion of the stem, or secured to it in any other approved way. A single passage 21 for the oil is preferred as it gives a free outlet.

The oil or other fluid together with the sand passes upwardly through the cage 22, outlet 21 and passages 19 at each upstroke of the plunger. In order to prevent the sand from passing backwardly into the pump barrel during the downstroke of the plunger, a conical cap or deflector 24 is arranged on the pump rod 12 above the passages 19 in the guide. This cap has an upper surface which projects downwardly and outwardly, and does not close the passages 19 and does not prevent oil from passing downwardly into the barrel.

The sand which is discharged with the oil strikes the inclined underside of the cap at the upstroke of the plunger, and much of it is deflected into the sand trap. The sand which is drawn up into the delivery pipe descends upon the inclined top of the cap during the downstroke of the plunger, and slides off the cap into the sand trap. The cap or deflector 24 is slideable on the pump rod, and is made of predetermined size and weight so that it will rise to a limited extent within the conical coupling sleeve 16 without closing the delivery pipe, the resistance being increased by the conical form of the coupling as the cap rises to let the oil flow freely through the passages 19.

What I claim is:

1. The combination, with a pump plunger provided with a pump rod, and a pump barrel provided at its upper end with a guide in which the pump rod is slideable; of a sand trap secured around the pump barrel, and a sand deflector provided with a conical upper surface and having a hole in which the pump rod is slideable, said sand deflector being normally supported by the said guide and free to rise with the liquid at each upstroke and operating to guide the sand into the sand trap at each downstroke.

2. The combination, with a pump barrel, a sand trap encircling the pump barrel, a delivery pipe secured to the upper end of the sand trap, and a pump plunger provided with a pump rod; of a guide for the pump rod which rests on the top of the pump barrel and which has packing devices at its lower part which are slid into the pump barrel, said guide having a discharge outlet at its top, and a conical cap or sand deflector mounted on the pump rod above the said discharge outlet and operating to guide the sand into the sand trap.
3. The combination, with a pump plunger provided with a pump rod, and a pump barrel provided with a guide at its upper part in which the pump rod is slid able; of a sand trap secured around the pump barrel, a conical coupling sleeve secured to the said sand trap and encircling the upper part of the said guide, a delivery pipe secured to the smaller end portion of the coupling sleeve, and a sand deflector arranged in the said coupling sleeve, said sand deflector being provided with a conical upper surface and having a hole in which the pump rod is slid able, said sand deflector being normally supported by the said guide and operating to deflect the sand outwardly into the sand trap.

In testimony whereof I have affixed my signature.

TOM J. BARGER.
